DESIGN FOR A RING

Gertrude S. Cohen and Emanuel Cohen,
Newark, N. J.

Application June 27, 1947, Serial No. 139,960

Term of patent 14 years

(Cl. D45—10)

To all whom it may concern:

Be it known that we, Gertrude S. Cohen and Emanuel Cohen, both citizens of the United States, residing at Newark, in the county of Essex and State of New Jersey, have invented a new, original, and ornamental Design for a Ring, of which the following is a specification, reference being had to the accompanying drawing, forming part thereof.

Fig. 1 represents a linear reproduction of the outer periphery of the ring of the present invention.

Fig. 2 shows an isometric front view of the same ring.

We claim:

The ornamental design for a ring, as shown.

GERTRUDE S. COHEN.
EMANUEL COHEN.
